(57) **CLAIM**

The ornamental design for a roller blind, as shown and described.

DESCRIPTION

FIG. 1 is a front view of a roller blind showing my new design;

FIG. 2 is a rear view thereof;

FIG. 3 is a left view thereof;

FIG. 4 is a right side view thereof;

FIG. 5 is a top view thereof;

FIG. 6 is a bottom view thereof;

FIG. 7 is a front perspective view thereof;

FIG. 8 is a rear perspective view thereof;

FIG. 9 is a front perspective view thereof in a roll-up configuration;

FIG. 10 is a rear perspective view thereof in the roll-up configuration;

FIG. 11 is a partially enlarged view showing the area 11 in FIG. 4;

FIG. 12 is a partially enlarged view showing the area 12 in FIG. 8; and,

FIG. 13 is a partially enlarged view showing the area 13 in FIG. 10.

The broken-line circles labelled “11”, “12”, and “13” indicate enlargement portions that form no part of the claimed design.

The portions of the roller blind shown in broken lines form no part of the claimed design.

1 Claim, 13 Drawing Sheets
